TOY TRAIN

Lloyd A. Nielsen, 4441 South Ave. W.,
Missoula, Mont. 59801

Filed Feb. 28, 1973, Ser. No. 336,690

Term of patent 14 years

Int. Cl. D21—01
U.S. Cl. D34—15 AJ

Fig. 1

Fig. 2

Fig. 3

Fig. 4

FIG. 1 is a perspective view of a toy train showing my new design;

FIG. 2 is a side elevational view thereof;

FIG. 3 is a top plan view of the right-hand member; and

FIG. 4 is a front elevational view thereof.

I claim:

The ornamental design for a toy train, as shown.
